UNITED STATES PATENT OFFICE.

ERNST H. ZOLLINGER, OF ZURICH, SWITZERLAND, AND HERMANN ROEHLING, OF MILWAUKEE, WISCONSIN.

METHOD FOR THE PRODUCTION OF GUAIACOL.

1,281,662.

Specification of Letters Patent. Patented Oct. 15, 1918.

No Drawing.

Application filed January 6, 1917. Serial No. 141,067.

To all whom it may concern:

Be it known that we, ERNST H. ZOLLINGER and HERMANN ROEHLING, citizens, respectively, of the Republic of Switzerland and the United States, residing, respectively, at Zurich, in the Republic of Switzerland, and at Milwaukee, State of Wisconsin, U. S. A., have invented a certain new and useful Improvement in Methods for the Production of Guaiacol, of which the following is a full, clear, concise, and exact description.

Our invention relates to a method for producing guaiacol from pyrocatechin. Prior to our invention of the process hereinafter claimed it was known that pyrocatechin could be methylated by means of methyl sulfuric acid or its alkali salts; for instance, Gorup-Besanez (Ann. 147, 247.) has described such a method. According to the Gorup-Besanez method, however, the yield of guaiacol is so poor that a commercial application of said method is not feasible. If, however, energetic methylating means are employed, as for instance dimethyl sulfate, which in view of its exceedingly poisonous qualities is little used for technical purposes, veratrol is produced in great quantities. (Ullmann Ann. 327, 104, Perkin and Weizmann Zentralblatt 07, 1, 406.)

We have found that when pyrocatechin and potassium methyl sulfate are intimately mixed and melted in the presence of veratrol guaiacol is produced in considerable quantities provided a weak alkaline compound, such as carbonate or bicarbonate of sodium is gradually added to the mixture. The great advantage of this method is obvious when consideration is given to the fact that pyrocatechin is inclined to undergo considerable changes in alkaline watery solutions. This method whereby we methylate pyrocatechin in veratrol as a solvent at a temperature of 180 degrees has the advantage that only one hydroxyl group is methylated in a yield exceeding 85 per cent. The fol-

lowing example will sufficiently illustrate our improved method.

Example.

11 grams of pyrocatechin are intimately 50 grated with 25 grams of potassium methyl sulfate and mixed with 15 grams of veratrol. To this mixture 25 grams of sodium bicarbonate is added in portions during two hours at a temperature of 160 to 180 degrees. 55 Upon getting cold, the reaction product is acidified and subjected to a steam distillation. From this distillate the guaiacol as well as the unchanged veratrol is recovered, according to known methods. The yield of 60 guaiacol amounts to 10.5 grams.

What we claim as new and desire to secure by Letters Patent of the United States is:

1. The herein described method of producing guaiacol from pyrocatechin, which 65 comprises subjecting the pyrocatechin to the action of an alkali salt of methyl sulfuric acid in the presence of veratrol, and adding a weak alkali metal compound to the material under treatment, while the mixture is held at a temperature of substantially 160 to 180 degrees.

2. The herein described method of producing guaiacol, which comprises subjecting pyrocatechin to the action of a methylating 75 agent, in the presence of veratrol, and adding a weak alkali metal compound.

3. The method of producing guaiacol from pyrocatechin which comprises subjecting the pyrocatechin to the action of a methylating 80 agent in the presence of veratrol at a temperature of from substantially 160 to 180 degrees and adding a weakly alkaline compound.

4. The method of producing guaiacol from 85 pyrocatechin which comprises subjecting the pyrocatechin to the action of a salt of methyl sulfuric acid in the presence of veratrol, adding a weakly alkaline compound while the mixture is held at a temperature of sub- 90

stantially 160 to 180 degrees, cooling and acidifying the reaction product, distilling the reaction product and separating the guaiacol from the distillate.

- 5 5. The herein described method of producing guaiacol, which comprises subjecting pyrocatechin to the action of a methylating agent in the presence of veratrol, adding a weakly alkaline compound while the mixture
- 10 is maintained at a temperature causing a

reaction of the methylating agent with the pyrocatechin.

In witness whereof ERNST H. ZOLLINGER has hereunto subscribed his name this 14th day of March, A. D. 1917.

15 ERNST H. ZOLLINGER.

In witness whereof HERMANN ROEHLING has hereunto subscribed his name this 5 day of May, A. D. 1917.

HERMANN ROEHLING.
